UNITED STATES PATENT OFFICE.

JOHN BRADLEY, OF NEWARK, NEW JERSEY, ASSIGNOR TO THE BRADLEY AUTOMATIC COUPLER COMPANY OF THE CITY OF NEW YORK.

CAR-COUPLING.

SPECIFICATION forming part of Letters Patent No. 339,261, dated April 6, 1886.

Application filed August 7, 1885. Serial No. 173,891. (No model.)

To all whom it may concern:

Be it known that I, JOHN BRADLEY, of the city of Newark, in the State of New Jersey, have invented a new and useful Improvement 5 in the Method or Manner of Coupling or Connecting Railway Freight-Cars Together Automatically.

My invention relates to car-couplings in which counterpoised coupling hooks or pins 10 are employed to secure the link; and it consists in the special construction of parts hereinafter described.

The following is a brief description of the drawings, and showing what each view represents.

Figure 1 represents the draw-head, also counterpoise coupling-pin engaged with link bearing upon seats, sectional view. Fig. 2 represents counterpoise coupling-pin depressed 20 from its seats in throat of draw-head, also chain-connection through slot and hole to surface of draw-head, sectional view. Fig. 3 represents counterpoise coupling-pin in regular form, with slotted hole for pivot-bearing 25 and slotted recess for chain-connection.

I take the regular draw-head A, and in its center and upon its under side, just back of the head of the draw-head, I cut a well or opening, a^a , about six inches long by two 30 inches wide and four inches deep, with a back rest, a^4 , or cross-bar, with beveled or sloping face a^6 in the center of this well or recess a^a , extending from one side to the other and entirely across the said well or recess, which 35 serves to strengthen the draw-head A, and also as a seat for the link or coupling D to strike against and hold in its place while coupling. This beveled or sloping face a^6 upon the back rest or cross-bar a^4 is for the purpose of 40 using links or couplings of any and all lengths, and to prevent the breaking of the back rest or cross bar, or the crippling of the links or couplings, by striking both ends at one and the same time. In this well or recess a^a , I 45 suspend a pivot or counterpoise coupling-pin, B, hung at an angle from the center to produce an eccentric motion or downward movement, so as to move within a limited space and not project below the under surface of draw-head A, for the purpose indicated. This counterpoise coupling-pin B, referred to, is made

in the form of an eccentric or cam, ending in a coupling-pin, b' ; for the purpose of engaging and forming a complete connection between two draw-heads, A, by means of an ordinary link or coupling, such as is now in use upon all railroads. The end of this counterpoise coupling-pin, which forms the coupling-pin b' , hangs in its seat across and through the throat or inner end of the beveled or sloping mouth E of the draw-head A. As the incoming link or coupling D strikes the beveled or sloping mouth E of the draw-head A it is brought into immediate contact with the face of coupling-pin B at the end b' of the counterpoise, which is immediately depressed by the contact. Being hung as an eccentric, it is readily displaced, and the link or coupling D passes over the end of the coupling-pin, which instantly enters or passes through the link or 60 coupling D to its original seats a^a . This counterpoise coupling-pin B drops, as it were, from the blow or pressure received from the link or coupling D as it enters or passes into the throat of the draw-head A, and the counterpoise coupling-pin B, moving within the 65 segment of a circle downward, raises the coupling-pin end b' through the link or coupling D, and the connection is made automatically and instantly. To make this connection more 70 secure, I provide seats a^a for each end of this coupling-pin b' to bear or draw against when subject to a draft, thus throwing the strain upon the strongest part of the draw-head A in just the same proportions and conditions 75 as in the old method of "link and pin," thus relieving the "pivot-pinion" from draft or strain, as the drawing-point is made upon the coupling-pin end b' of the counterpoise coupling-pin B. The results are all produced automatically and instantly. The upper edge of 80 this counterpoise coupling-pin B is provided with an eye, b^3 , to which is attached a chain, C, which passes through the slot b^4 to a hole, a^5 , cored or bored at an angle to correspond 85 with the eccentric motion of the counterpoise coupling-pin B. This hole a^5 extends through the upper face of the draw-head for the purpose of allowing the chain C to move freely 90 as the counterpoise coupling-pin B is moved. This chain extends to the top of the freight-car, for the purpose of uncoupling or releas-

ing the counterpoise coupling-pin B from the link or coupling D by simply pulling the chain C upward toward the top of the car, and to either or both sides of the car and at its end 5 outside.

The throat of the draw-head A is so constructed that the link or coupling D can be set or placed in a horizontal position to make the connection from the opposing draw-head to without being depressed; or it can be left depressed at an angle, so as to engage or couple at any difference in height of the opposing draw-heads.

I am aware that counterpoised coupling-15 hooks and draft-seats formed in the draw-head to act in conjunction therewith have heretofore been known, and I do not seek to cover such construction, broadly.

What I claim as my invention, and desire to 20 cover by Letters Patent, is—

1. In a car-coupling substantially such as described, the counterpoised coupler B, formed with the eccentric portion b, the upper side of which is formed with a longitudinal groove, 25 b⁴, and pull-bolt b³, for the reception of the

pull C, in combination with a draw-head, A, formed in its upper side with the pull-hole a⁵, substantially in the manner and for the purpose described.

2. In a car-coupler substantially such as 30 described, the counterpoise B, formed with the elongated slot b², for the reception of the pivot a³, the longitudinal groove b⁴, pull-bolt b³, and pull C, and the coupling-hook b', in combination with the draw-head formed with 35 the draft-seats a' and a², and the pull-hole C, substantially in the manner and for the purpose described.

3. In a car-coupling substantially such as 40 designated, the combination, with the counterpoised coupling-pin, of a back rest or cross-bar formed in the draw-head in such relation to the body of the said counterpoise coupling as to afford a support for the inner end of the coupling-link, substantially in the manner and 45 for the purpose described.

JOHN BRADLEY.
